UNITED STATES PATENT OFFICE.

JOHN H. LORIMER, OF PHILADELPHIA, PENNSYLVANIA.

DRYING-MACHINE.

SPECIFICATION forming part of Letters Patent No. 445,226, dated January 27, 1891.

Application filed May 26, 1890. Serial No. 353,127. (No model.)

To all whom it may concern:

Be it known that I, JOHN H. LORIMER, of the city and county of Philadelphia, and State of Pennsylvania, have invented an Improvement 5 in Drying-Machines, of which the following is a specification.

My invention has reference to drying-machines adapted to dry textile fibers or fabrics; and it consists of certain improvements, which 10 are fully set forth in the following specification and shown in the accompanying drawings, which form a part thereof.

In carrying out my invention I provide a closed chamber through which endless aprons 15 of perforated or slatted work are caused to pass, and are preferably guided back and forth within the compartments and brought to the outside, so that the materials may be laid upon the slatted work or apron at a point 20 outside of the closed chamber and then be conveyed through the closed chamber, and when dried passed out of the same again for delivery. In connection with this endless apron there is employed one or more endless aprons 25 located wholly within the closed chamber and adapted to work in conjunction with the first-mentioned apron for conveying the textile fibers back and forth through the chamber. In connection with these features I provide the 30 chamber with inlet-ports for air or gas of any description, either hot or cold, and exhaust fans or suction-creating devices so arranged with respect to the apron that the air is drawn through the drying-chamber and through the 35 perforated or slatted aprons. By this means material is conveyed back and forth through the drying-chamber, and during its transit is subjected to strong currents of air or gas which take up the moisture and carry it to a 40 point external to the drying-chamber, and thereby quickly and thoroughly dry the textile fiber or fabric being conveyed through the machine.

This machine is particularly adapted to the 45 treatment of wool, cotton, or other loose fibrous material.

Referring to the drawings, Figure 1 is a sectional elevation of a drying-machine embodying my invention on line $y-y$ of Fig. 2. Fig. 50 2 is a sectional plan view of same on line $X-X$

of Fig. 1, and Fig. 3 is a cross-sectional elevation on line $Y-Y$ of Fig. 1.

A is the closed drying-chamber, and is provided with an inlet-aperture C and an outlet-aperture D for the apron E, and one or more 55 inlet-apertures B for the drying air or gas, and one or more outlet-apertures k for the escaping moist air or gases, leading to the suction-fans or exhausters K. The endless apron E is guided over wheels I and H at one end of 60 the machine, taking, preferably, an upward oblique direction, and then passes through the aperture C to the interior of the drying-chamber. When this apron reaches the distant side of the drying-chamber, it passes 65 over a guide-roller G, and thence backward and forward over a series of similar guide-rollers G and emerges through the aperture D of the drying-chamber, passing around the exterior wheel F and thence back to the 70 first-mentioned guide-wheel I. Working in conjunction with this endless apron E is one or more endless aprons M, arranged wholly within the chamber A and guided around guide-wheels L and the guide-wheels G. The 75 endless aprons M, as shown, lie close to the endless apron E and project at the places where they pass around the wheel L, so that the textile material which may be moved around the left-hand rollers or guide-wheels G may be 80 properly received upon the endless aprons M immediately below. If desired, the rollers or wheels L may be of greater diameter than that shown in full lines, so as to form pockets between the aprons to receive the material, 85 as indicated in dotted lines in Fig. 1.

In place of using two such endless aprons M it is evident that one endless apron may be employed, as indicated in dotted lines, so that it would pass over the upper roller L, 90 thence around upper right-hand wheel G, thence around lower left-hand wheel G, thence around lower right-hand wheel G, thence under lower guide wheel or roller L, and thence to upper guide wheel or roller L. These aprons 95 are preferably formed of two sprocket-chains, between which are metallic slats, as indicated in Fig. 2, so as to form a good support for the material and at the same time permit the free passage of air or gases through it. It is 100

quite evident that the aprons might be made of wire or cords, and in fact might be made in any suitable manner, so as to form open work, though I prefer to form them as first described.

Wind-guards S may be arranged along the sides of the machine to prevent passage of air around the aprons. They insure the air all passing through the aprons and materials being treated while being conveyed by the aprons.

The material will be placed upon the endless apron E, outside of the drying-chamber, and after passing upward will enter the opening C, and after being carried through the drying-chamber to the distant side it will pass around the wheel G and then between the aprons E and M, and so on until it finally emerges from the aperture D. During its passage through the machine the exhausters K cause a strong suction and insure the drying air or gases, either cold or heated, as may be desired, to pass through the material as it is conveyed through the drying-chamber.

J is the drive or power wheel. It is quite evident that the aprons may be made to travel in the opposite directions, if desired; or, if preferred, the air-currents may be caused to pass upward through the machine by connecting the exhauster with the apertures B, as indicated in dotted lines at K', in which case the dryest air would meet the dryest portion of the material being treated and just before it passes out of the machine.

The endless aprons M are driven by contact with the apron E and the sprocket-wheels G at the right-hand portion of the machine, and a common speed to the aprons is therefore insured.

I do not limit myself to the mere details of construction, as it is evident that such details might be modified in various ways.

Having now described my invention, what I claim as new, and desire to secure by Letters Patent, is—

1. In a drying-machine, the combination of a closed chamber provided with apertures for

the admission of a drying medium, such as air or gas, with exhausters or fans for creating a current of air or drying-gas through said machine in a vertical direction, an endless apron of open-work passing from the outside of the drying-chamber to the interior thereof through an aperture, thence back and forth through said drying-chamber and to the exterior thereof through a second aperture, guide-wheels for said apron, one or more endless aprons located wholly within the drying-chamber and moving in close contact with said first-mentioned apron, and guide-wheels for said last-mentioned apron or aprons, the said aprons passing backward and forward through the drying-chamber directly in the path of the drying gases or air.

2. The combination of a drying-chamber A, having one or more apertures for the admission of air or gases, one or more fans or exhausters K, for causing a circulation of the drying air or gas, located at or near the opposite portion of the drying-chamber, an endless apron E, of open-work, passing backward and forward through the drying-chamber, guide-wheels G within the drying-chamber for guiding the said endless apron, guide-wheels H, I, and F, exterior to the drying-chamber, for guiding the said apron exterior to said drying-chamber for receiving and delivering the material being dried, one or more endless aprons M, arranged to travel in close juxtaposition with the endless apron E at points wholly within the drying-chamber, and one or more guide-rollers L for said aprons M, for bringing the said aprons M beyond the apron E, where it passes over the adjacent guide-wheels G, whereby said aprons M may receive and support the material being dried as it is conveyed over and around the last-mentioned guide-wheels G.

In testimony of which invention I have hereunto set my hand.

JOHN H. LORIMER.
